LABEL TACKING MACHINE

Morris S. Malek, Bronx, N. Y., assignor of one-half to McCurrach Organization Incorporated, New York, N. Y., a corporation of New York

Application November 10, 1941, Serial No. 418,584

3 Claims. (Cl. 112—104)

This invention relates to devices for tacking labels.

One object of the invention is to provide a device having improved means for carrying a label and a member to which the label is to be tacked in a predetermined path so that the label can be secured with great rapidity.

Another object of the invention is to provide a device comprising a tacking sewing machine and carrier means for a label and member whereby the tacking is effected at the corners of the label by improved coordination with the feeder element of the tacking machine.

Another object of the invention is the provision of a device of the nature set forth having improved means for tacking labels of different sizes at the corners thereof, while automatically carrying and guiding the label to different tacking positions.

Another object of the invention is to provide a device of the type mentioned having improved means whereby a label can be tacked to a large article such as a necktie, without the need for turning the latter, and while carrying and guiding the label and article to different tacking positions determined by a cam means.

Another object of the invention is to furnish a tacking sewing machine and a label guide carrier in such improved coordination therewith as to permit the presser foot to be dispensed with in tacking the label at its corners as determined by the guide carrier.

Other objects and advantages of the invention will become apparent as the specification proceeds.

With the aforesaid objects in view, the invention consists in the novel combination and arrangement of parts hereinafter described in their preferred embodiments, pointed out in the subjoined claims, and illustrated in the annexed drawings, wherein like parts are designated by the same reference characters throughout the several views.

In the drawings:

Figure 1 is a diagrammatic view in side elevation showing a device embodying the invention.

Fig. 2 is a diagrammatic view in front elevation thereof.

Figs. 3, 4, 5 and 6 are enlarged fragmentary plan views of a device according to the invention showing successive positions to illustrate a cycle of operation, with some parts removed and shown in dot-dash lines in Fig. 4, and other parts removed in Fig. 5, and still other parts removed or in section in Fig. 6.

Fig. 7 is a view in side elevation showing my improved attachment for a tacking machine.

Fig. 8 is an enlarged view in elevation showing a locking control for an article to which the label is to be tacked.

Figs. 9 and 10 are enlarged sections on lines 9—9 and 10—10 respectively of Fig. 3.

Fig. 11 is an enlarged section on line 11—11 of Fig. 4, showing the article and label that is being attached thereto, and the tacking means.

Fig. 12 is a vertical front view with parts in section, on the broken line 12—12 of Fig. 7.

Fig. 13 is a fragmentary bottom plan view.

Fig. 14 is a vertical sectional view on line 14—14 of Fig. 3.

The advantages of the invention as here outlined are best realized when all of its features and instrumentalities are combined in one and the same structure, but, useful devices may be produced embodying less than the whole.

It will be obvious to those skilled in the art to which the invention appertains, that the same may be incorporated in several different constructions. The accompanying drawings, therefore, are submitted merely as showing the preferred exemplification of the invention.

Referring in detail to the drawings, 15 denotes a device embodying the invention. The same may include any conventional tacking sewing machine, for example, of the type manufactured by the Singer Manufacturing Co. The same may include a head 17 carrying a vertically reciprocating needle 18, and a releasable presser foot 19. The latter may consist of two fingers which are swingable upwardly into released position as in Fig. 1 or downwardly into operative position as in Fig. 2. In any case, the presser foot cooperates with a feeder element 20 carried by the bed portion 22 of the machine, and operated by any suitable mechanism, not shown, in order to permit the goods to be tacked. Operation of the machine 16 is initiated by a foot pedal 23 pivoted at 24 and actuating a rod 25, it being understood that the machine 16 stops automatically when a tack is completed and may automatically sever the thread in such a manner that the needle 18 remains threaded. A pedal 26, arranged like that at 23 may operate the presser foot 19, in any suitable manner, or the presser foot may be moved by hand.

Co-operating with the tacking machine 16 is an attachment 21 embodying the invention. The same may comprise a base member 28 having an upright wall 29 from the front side of which project integral bracket arms or flanges 30, 31, the

former being located intermediate of the top and bottom planes of the base 28, and the latter being located along the top plane of the base and being parallel to the bracket arm 30. Centrally formed in the top of the wall 29 and flange 31 is a continuous recessed guideway 32 for a slide 33 hereinafter described. Formed in the lower portion of the wall 29 toward the right thereof is a bore 34 extending therethrough for a cylindrical pull bar or cam actuator 35 hereinafter described. Extending rearward from the wall 29 are integral wall members including a bottom wall portion 36 and a side wall portion 37 which may serve for securing the attachment 27 to any suitable table or other support, not shown, with the side wall 37 also carrying at its rear top portion a bearing 38 for mounting an actuator means for the pusher bar 35 as hereinafter described.

The slide 33 is retained in the recess 32 by a top plate 39 fastened to the wall 29 as by screws 40. Secured on the top plate 39 are four guide pins 41 which are snugly received in corresponding holes of a removable interchangeable plate 42 which carries an integral stationary cam 43 hereinafter described. For securely holding down the cam carrying plate 42, a stud or trunnion 44 is fixed to the bolted plate 39 and extends into a corresponding hole in the plate 42 and above the same. This trunnion may carry any releasable cam lock, that may include a lock pin 45 as shown in Fig. 7 engageable in a helical cam groove 46 of a sleeve 47 that receives the trunnion 44. The lower end of the cam groove 46 is open to receive the lock pin 45, and on turning the sleeve or hub 47 as by a handle 48 integral therewith, a powerful downward pressure is exerted on the cam carrying plate. The lock pin 45 may be made removable from the trunnion 44, or a slot, like a keyway 49, see Fig. 14, may be provided so that the plate 42 may be moved upward past the pin 45 when the handle 48 has been moved to cause the cam 46 to release the lock pin 45.

Carried by the slide bar 33 is a head 50 having a recessed guideway from end to end thereof to receive a second slide bar 51, which extends transversely of the first slide bar 33. Retaining the slide bar 51 in its guideway is a top plate 52 suitably secured to the head 50 to form a rigid unitary structure therewith. Extending fixedly through the slide bar 51 is a pin providing an upper pin portion 53 and a lower pin portion 54, the former serving as a follower for the cam 43, the latter as actuator, all as hereinafter described. The pin portions 53, 54 extend through aligned slots 50a formed in the respective members 52, 50 as shown in Figs. 4 and 14.

The cam 43 is of the positive type being formed by a groove 55. Preferably the latter defines a closed path and is desirably of rectangular shape as clearly shown in Figs. 3, 4 and 5. This cam groove faces downward to engage the follower pin 53 of the slide bar 51, and of course the cam 43 forms an overhanging structure to permit the desired freedom of movement of the head 50. Accordingly the slide bar 51 is capable of moving according to the closed path of the cam 55, since it traverses its head 50 in one path, while the head 50 with its slide bar 33 traverses the wall 29 and the cam 55 in a direction at right angles to the first mentioned path. Hence the article holding means 56, hereinafter described, and which is affixed to the slide bar 51 follows the closed path of the cam 55, and, as will be apparent herein-after, the direction of movement is counterclockwise.

For causing the follower 53 to move along the cam 55 as stated, the pull rod 35 is pivotally connected at 57 to an arm 58 that forms a bell crank lever with the arm 59, said lever being carried by the bearing 38. For example, the arms 58, 59 may be rigidly affixed to the shaft 69 of the bearing 38, the arrangement being shown in Figs. 3 and 7. An adjustable set screw 61 fixed to the wall 29 may engage the arm 58 to limit forward movement of the pull bar 35. A rod or wire 62 may be connected to the arm 59 and to a pedal 63 to facilitate actuation, and any spring means, such as a tension coil spring 64 connected to the arm 59 and detachably engaged with an upright rod 65 on the plate 42, may serve to cause forward projection of the pull bar 35 to return the same to initial position determined by the set screw 61.

Journalized in the bracket arm 30 at its forward end portion is a stub shaft 66, which is coaxial with the center of the cam groove 55 of the cam 43. Fixed on the lower end portion of the shaft 66 are one or more ratchet wheels 67 which in this case may have only four equally spaced teeth. A pawl 68 for the ratchet wheel 67, having an upstanding pawl tooth 68a, may be pivotally mounted at 69 on the pull bar 35 and may be pressed into engagement with the ratchet wheel by a strip spring 70. The latter may be affixed to the pull bar 35 at 71 and may be set into the side of the pull bar so as not to obstruct retraction into the guide passage 34. When the pedal 63 is depressed, the bar 35 is pulled backward causing the pawl 68 to cause a quarter turn of the ratchet wheel 67. To prevent overriding, a square block or plate 72 may be centrally fixed on the bottom end portion of the shaft 66, and may be laterally engaged by a strip spring 73 which may be affixed to a side of the wall 29.

Fixed to the upper end portion of the shaft 66 is a rotary means such as an arm 74 to the free end of which is connected a tension coil spring 75, the other end of which is connected to the pin portion 54. Hence rotation of the ratchet wheel 67 will cause rotation of the arm 74, with the spring 75 pulling the pin 54 and hence the slide bar 51 to cause the pin 53 to follow around the cam 55. By employing a yielding means such as the spring 75, the non circular contour of the cam 55 is allowed for, and the cam 55 may be considerably greater in length than in width to take care of various rectangular labels. When the ratchet wheel is moved through a quarter turn, on a single reciprocation of the pull bar 35, the arm 74 moves a quarter turn and causes the follower pin 53 to move along one side of the cam 55, with the arm resting in a position diagonal to the cam groove as shown in Fig. 4, so that the spring 75 tends to pull the follower 53 into the corner of the cam groove.

To assure a proper and accurate dwell of the follower pin 53 in the corners of the cam groove, the pawl and ratchet structure may be arranged to form a stop. Thus the teeth of the ratchet wheel 67 are arcuately formed as shown in Fig. 13 to reliably engage the pin 68a of the pawl 68, while the pawl itself may be laterally stopped by a disc or collar 76 on the shaft 66, see Fig. 13. Rearward pull on the bar 35 may be stopped by the front end hook 76a adapted to engage the collar 76 on retraction of the pawl. Thus the strip spring 70 presses the pawl against the collar 76 as a stop. With the location of the pawl pin 68a thus reliably deter-

mined, the spring 75 is arranged to lie off the diagonal relative to the cam 55, so that this spring 75 tends to force the ratchet wheel 67 snugly against the pawl pin 68a. In other words, the pawl pin acts as a stop, made effective by the spring 75 which also retains the follower pin 53 at rest in the corners of the cam groove 55 to assure reliable positioning of the article holder 56.

The article holder 56 may comprise a plate 77 integral with the slide bar 51. This plate 77 is very thin, for reasons later stated, it may have at its bottom a marginal reinforcement rib 79, while a broad reinforcement rib 78 on the top rear portion is in alignment with the slide bar 51. The plate 77 may slidably seat on the bed portion 22 of the tacking machine, with the reinforcement 78 clearing the front and sides thereof. Formed in the plate 77 are a plurality of openings 80, which may be four in number, corresponding to the tacking positions as determined by the cam 55. The needle 18 and the feeder element 20 of the tacking machine may enter these openings to perform the tacking operations. If labels of different sizes are to be tacked, the openings 80 should be made sufficiently large to accommodate other tacking positions that may be determined by a different cam 55. Thus in Figs. 3 to 6, the tacking means is shown at outer corners of the openings indicating the setting for the largest size of label that can be tacked with the attachment 56. By making the plate 77 very thin, the fabric that is being tacked is accessible to the feeder element 20, and wrinkling of the fabric downwardly into the openings 80 by pressure of the presser foot 19 is avoided. Since the feed dog 20 moves vertically as well as horizontally, it enters an opening 80 only upon its upward movement. When the needle is raised at the completion of a tacking operation, the feed dog is lowered to clear the opening 80 so that the plate 77 can be shifted to tack another corner of the label. While the entrance of the feed dog into openings 80 is desirable, it is not essential.

For holding down an article or member, such as a necktie N, on the plate 77, a member 81 may be provided having a forked or frame-like pressure portion 82 which not only bears down on the article but forms a frame or guide for accurately setting the label. This guide may serve even with labels of different sizes. Since it lies beyond the openings 80, no obstruction in tacking is caused. For operatively mounting the member, the same may have a rear downward extending flange 83 having holes freely pivotally receiving the screws 84 carrying expansion coil springs 85 which press the flange 83 forward. To cause a downward tilting, the flange has at its lower edge a forwardly extending lip 86 bearing on the part 79, and thus the springs 85 cause the fingers 82 to press down on the plate. For lifting the fingers 82, a rod 87 is slidable in a groove 88 of the part 79, this rod carrying upward projecting sloping cams 89 that are received in openings 90 of the member 81. The rod 87 is reciprocated in its groove by a finger piece or arm 91 pivoted at 92 on the part 79 and having pin and slot engagement at 93 with the cam rod 87. In the position shown in Fig. 4, the rod 87 has been slid leftward with the cams 89 lifting the member 81 to cause an upward tilting of the fingers 82. When the finger piece 91 is released, the pressure of the springs 85 is effective to cause the member 81, bearing downward on the sloping sides of the cams 89, to

cause the latter to move rightward with a corresponding movement of the finger piece 91, whereby the fingers 82 are automatically moved to clamping position.

For holding down a label L on the article or necktie N, as shown in Fig. 11, a label plate 94 may be used, having corner cut outs in register with the openings 80 to form a somewhat cross shaped part. This label plate 94 is mounted on an arm 95 which is swingably carried by a locking device 96 for retaining the label plate elevated when swung out of operative position as shown in Fig. 3. The locking device 96 may include a stationary headed rod 97 rigidly affixed to the reinforcement 78 of the plate 77. Slidable on the rod 97 is a hub or sleeve 98 having a finger piece 99, see Fig. 3, whereby the sleeve 98 may be pushed upward against the pressure of an expansion coil spring 100 acting between the sleeve and the head of the rod 97. To this sleeve, the arm 95 is rigidly affixed. To lock the arm 95 in elevated position, the rod 97 is formed with a pin 101 engageable in a slot or cam groove of the sleeve, which may include a horizontal cam 102 and a vertical cam 103. In the position of Fig. 8, the device is in normal label holding position as in Fig. 4. To release and prepare for a new label, the sleeve 98 is moved upward, as by the finger piece 99, and is then turned to swing the label plate 94 out of the way as in Fig. 3. The pin 101 rides in the cam 103 and when it enters the cam 102, the sleeve 98 is locked against downward movement by the spring 100, and the sleeve may now be freely turned with the pin riding in the horizontal slot or cam 102. The operation of the machine will now be briefly described. The operator first selects the proper cam plate 43 according to the size of the label, engages it with the pins 41 and stud 44, and applies the locking device 47, whereupon the follower 53 enters the cam groove 55. Moving the finger piece 91 leftward, the fingers 82 are raised and the article or necktie N slid thereunder to be held by said fingers. Now, with the openings 80 concealed, a label L is applied with the member 81 and its fingers 82 acting as a position indicator for the label. The label holder 94 is then swung forward and snaps down on the label under the tension of the spring 100. The tacking machine 16 is now operated to form tacks through the successive openings 80 in a counterclockwise direction, the feeder element and needle, 20 and 18 respectively, engaging through the openings 80 of the very thin plate 77. When a tack is completed, and the sewing machine comes to rest, the pedal 63 is pressed to pull the bar 35 rearward so that the pawl 68 moves the ratchet wheel 67 a quarter turn, and hence correspondingly moves the arm 74 and the spring 75 carried thereby. Thus a pull is exerted on the pin 53, 54 of the slide 51 causing it to move along one side of the closed cam 55 from one corner to another, coming to rest for the next tacking operation. By reason of the provision of the slides 33 and 51 all required movements are accomplished, and the holder 56 carried by the slide 51 is moved through a complete cycle back to initial position. In making these movements the spring 75 allows for the non circular path of movement and retains the cam follower 53 in the cam corners, and being offset from the true diagonal of the cam 55, tends to exert a clockwise force in all four positions, with the pawl pin 68a serving as a stop, to thus assure that the follower 53 will lie exactly in the

corners of the cam 55. The tacking of the label is now completed.

During the tacking of the label at its four corners, the only additional operation required is that of the presser foot 19 which must be raised and lowered for each tacking. However, the presser foot may be omitted, because the label plate 94 may itself act as a presser foot not only because it powerfully presses down on the label and necktie, but also because it lies in very close proximity to the feeder element 20 of the sewing machine. This relation will occur in tacking labels of different sizes in which the position of the needle relative to the openings 80 will be varied, as determined by the interchangeable 15 cam 55.

If desired, the label may be affixed to the article or necktie by a removable clamp, before being applied to the machine. This would avoid the individual positioning of the article and label on the machine. The clamp may be arranged to line up with the frame-like structure of the holder, for example, with the spaced fingers thereof and the raised rear part, so that the label would thus be held in proper relation to the 20 needle. With such a removable clamp one operator could be engaged in clamping the labels to the neckties, and another operator could cause the labels to be tacked to the neckties by the machine, and remove the clamps when the tacking has been completed.

I claim:

1. A device including a support, a first means mounting the support for reciprocatory movement in one path, a second means for mounting the first means for reciprocatory movement in a path transverse to the first path, a relatively stationary cam defining a closed path and cooperating with the first mentioned means for guiding the same, and a rotary means coacting with the support for actuating the same to follow said path with operative action of the first and second means in movably mounting the support, said rotary means being coaxial with the center of said cam, said rotary means having an arm, 25

and a tension spring connecting said arm and said support, and control means for causing intermittent angular motion of the rotary means, the control means having a stop means for holding the support in a predetermined position against the tension of said spring.

2. A device including a support, a first means mounting the support for reciprocatory movement in one path, a second means for mounting the first means for reciprocatory movement in a path transverse to the first path, a relatively stationary cam defining a closed path and cooperating with the first mentioned means for guiding the same, and a rotary means coacting with the support for actuating the same to follow said path with operative action of the first and second means in movably mounting the support, said rotary means being coaxial with the center of said cam, said rotary means having an arm, and a tension spring connecting said arm and said support, said rotary means being intermittently angularly movable, and a releasable stop means for holding the support in positions corresponding to the corners of said path against the tension of said spring.

3. A device for holding together a label and a member that are to be tacked together at spaced points, including a support for said label and member, means for clamping said label and member to said support, said support having openings at which the label and member are tacked together, a rotary means intermittently angularly movable, a relatively stationary cam defining a closed path, mounting means for said support adapted to follow the path of said cam, the rotary means being coaxial with the center of said cam and having a rotary arm, a tension coil spring connecting said arm to a portion of the mounting means to cause the support to dwell in the corners of its path, and means releasably holding the mounting means in positions corresponding to the corners of said path and against the tension of said spring.

MORRIS S. MALEK.
